UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

INSULATING SUPPORTING MEANS.

1,101,058.

Specification of Letters Patent. Patented June 23, 1914.

Application filed April 9, 1914. Serial No. 830,588.

To all whom it may concern:

Be it known that I, FRANK E. CASE, a citizen of the United States, residing at Schenectady, in the county of Schenectady, State of New York, have invented certain new and useful Improvements in Insulating Supporting Means, of which the following is a specification.

My invention relates to insulating supporting means, and more especially to the support of third rails for electric railways, and it comprises various novel features of construction and combinations and arrangements of parts that will be hereinafter set forth by the detailed description of the best forms thereof at present known to me.

Among the advantages obtainable in connection with my invention are simplicity and strength of construction; ruggedness and reliability in service, and ease of installation; also,—and of great importance when the invention is employed in supporting a third rail,—thorough insulation of all exposed parts. How these and other advantages may be obtained in accordance with my invention will appear hereinafter, and the scope of the invention will be indicated in my claims.

In the accompanying drawing, Figure 1 is a side view of one form of insulating supporting means or bracket structure constructed in accordance with my invention, the third rail supported by it being shown in section. Fig. 2 is a plan view of the structure shown in Fig. 1, the lower portion and the third rail being omitted. Fig. 3 is a fragmentary sectional view through the upper portion of the structure, at right angles to Fig. 1. Fig. 4 is a fragmentary view of the upper portion of a modified structure, most of the parts being in section.

Referring first to Figs. 1, 2 and 3, it will be seen that the supporting means or bracket structure shown comprises a pedestal supporting member 1 adapted to be mounted and secured on the roadbed, as by lag screws 2 extending through holes in its foot into a cross-tie. On the top of the pedestal 1 a pair of insulators 3, 4 (of bisque, porcelain, or other material) are secured by means of a bolt part 5 extending through them, and between the insulators 3, 4 is clamped an arm member 6 by which the third rail 7 is carried. The pedestal 1

has at its top a web 8 through which the bolt 5 passes and which has at its lower side ridges 9 for engaging the square head of said bolt and preventing it from turning, and on top of the upper insulator 4 is a sort of cap piece 10 with projections 11 for similarly engaging a square washer or nut-lock 12 beneath the nut 13. This cap piece 10 has a projection 14 adapted to engage the ordinary inverted wooden trough third rail cover to prevent longitudinal shifting thereof or otherwise assist in keeping it in place. At the outer end of the arm 6 is a sort of jaw 15, and at diagonally opposite corners of this jaw are teeth or lugs 16 that extend beneath the upper head of the reversible I-shaped third rail 7. This form of jaw 15 has the advantage that the upper head of the third rail 7 can be introduced into it sidewise as well as endwise, which facilitates the work of the construction gang. As shown, the jaw 15 has a clearance about the rail head which is ample for the downward movement of the bracket structure that occurs when a car wheel passes over the cross-tie on which its pedestal 1 is mounted.

The pedestal 1, it will be seen from Fig. 3, has relatively inclined top surfaces 20, and the insulator 3 has relatively inclined lower surfaces 21 adjacent and conforming to those of the pedestal, and by this mode of engagement the insulator 3 is kept in proper position and prevented from turning with reference to the pedestal. Each of the insulators 3, 4 has relatively inclined surfaces 22 adjacent the other, and the arm member 6 has at its end which is clamped between the insulators relatively inclined surfaces 23 adjacent and conforming to the surfaces 22, and by this mode of engagement turning of the arm member 6 with reference to the lower insulator 3 is prevented,—as also turning of the upper insulator 4 with reference to the arm member and the lower insulator. As shown, the upper insulator 4 is made exactly like the lower one, and the cap piece 10 has lower relatively inclined surfaces corresponding to the upper relatively inclined surfaces 24 of said insulator 4, so that turning of the cap piece thereon is prevented.

Still referring to Figs. 1, 2 and 3, it will be seen that the holes in the insulators 3 and 4 through which extends the bolt 5

gradually enlarge toward adjacent sides of said insulators, and that the portion of the arm member 6 that lies between the insulators 3 and 4 has an opening for the bolt 5 large enough to give an ample clearance. The arm member 6 has at its edge a flange which extends across the end 27 between the insulators 3 and 4 and is received in grooves 28 in them, and there is also a transverse 10 flange 29 that lies against the edges of the insulators and coöperates with the end flange at 27 in preventing movement of the arm 6 in its own longitudinal direction. At the 15 sides of the bolt opening in the arm 6 the angles at the root of the edge flange are filled in to form the inclined surfaces 23, so that the section of metal here is triangular as shown in Fig. 3. At their adjacent edges the insulators 3 and 4 are flared outward 20 into heavy flanges 30 that extend around the portion of the arm 6 between them, so as to afford ample protection; thus there are in effect U or horse-shoe grooves of varying form in the adjacent sides of the insulators 3 and 4 for receiving corresponding ridges of the arm member 6. Between the insulators and the parts clamped together with them—that is to say, the top web 8 of the pedestal 1, the arm 6, and the 25 cap pieces 10—are placed several thicknesses of heavy insulating fiber or cardboard or other material adapted to afford a cushion and prevent excessive local strain on the material of the insulators in consequence of 30 the parts being clamped tight together. At the middle of each of the inclined surfaces 22, 23 and 25 is a shallow channel or depression intended to insure a good bearing at the corners of the insulators.

40 Referring, now, to Fig. 4, it will be seen that in the construction here shown there are no relatively inclined surfaces such as shown in Figs. 1 and 3, but that on the contrary the top of the pedestal 41 and the upper and lower surfaces of the insulators 43 and 44 are flat. It will further be seen that the portion of the arm 46 between the insulators 43 and 44 is flat on both sides, and that it is kept in place with reference to the 45 insulators by sheet metal parts 47 with oppositely turned inner and outer flanges that engage in the bolt opening of the arm 46 and in grooves 49 in the adjacent sides of said insulators. The outer flanges of the 50 parts 47 and the grooves 49 may be circular or may be rectangular or U-shaped. The insulators 43 and 44 are kept properly located with reference to the pedestal 41 and to the bolt member 50 by sheet metal parts 55 51 and 52 having outer flanges that fit

around the ends of the insulators and also having central holes which approximately fit the bolt. The part 51 is placed between insulator 43 and the top of the pedestal and may if desired be of paper, fiber, or other cushioning material rather than of metal, and the part 52 is arranged by way of a cap on the top of the insulator 44. The flanges of the parts 51 and 52 and the corresponding ends of the insulators 43 and 44 may be either circular or more or less rectangular. The third rail shown is of ordinary T section, and the outer edge of its base flange is held by a sort of claw 55 bolted to the outer end of the arm 46.

What I claim as new and desire to secure by Letters Patent of the United States, is:—

1. Insulating supporting means comprising a supporting member, a pair of insulators secured thereto by a part extending through them, and a member associated with the element to be supported clamped between said insulators.
2. Insulating supporting means comprising a supporting member, a pair of insulators secured thereto one of which is so engaged therewith as to be prevented from turning with reference thereto, and a member associated with the element to be supported clamped between said insulators and so engaged with one of them as to be prevented from turning with reference to said supporting member.
3. Insulating supporting means for a third rail comprising a pedestal adapted to be mounted on the road-bed, a pair of insulators secured on the top of said pedestal, and an arm for carrying a third rail having one end clamped between said insulators.
4. Insulating supporting means for a third rail comprising a pedestal adapted to be mounted on the road-bed and having relatively inclined top surfaces, a pair of insulators secured on the top of said pedestal by a bolt passing through them, one of which has relatively inclined surfaces adjacent and conforming to those of the pedestal, and has also relatively inclined surfaces adjacent the other insulator, and an arm for carrying the third rail clamped between said insulators and having relatively inclined surfaces adjacent and conforming to those of the insulator next the pedestal.

In witness whereof, I have hereunto set my hand this 8th day of April 1914.

FRANK E. CASE.
